UNITED STATES PATENT OFFICE.

ROBERT W. JAMISON, OF MITCHELL, SOUTH DAKOTA.

COMPOUND WALKING BEAM FOR WELL-DRILLING RIGS.

1,417,604.

Specification of Letters Patent. Patented May 30, 1922.

Application filed July 24, 1920, Serial No. 398,667. Renewed October 29, 1921. Serial No. 511,450.

To all whom it may concern:

Be it known that I, ROBERT W. JAMISON, a citizen of the United States, residing at Mitchell, in the county of Davison and State of South Dakota, have invented certain new and useful Improvements in Compound Walking Beams for Well-Drilling Rigs, of which the following is a specification, reference being had to the accompanying drawings.

This invention relates to walking beams such as are used in connection with well drilling machines.

One object of the invention is to provide for a relatively slow upward movement of the cable supporting the well drilling tools with a relatively fast drop of the cable.

A further object is to provide means whereby the movement of the drill cable may be halted without having to stop the movement of the crank shaft or other machinery whereby reciprocation is ordinarily given to the cable, and in this connection it is an object of the invention to provide a walking beam consisting of two sections, one of which is operatively connected to the drill cable, and the other of which is operatively connected to the power operated means for oscillating the walking beam, and to provide means whereby these two sections may be shifted into or out of operative engagement with each other to thereby permit the stoppage of that section carrying the drill cable without necessarily stopping the movement of the crank shaft or other oscillating means.

Other objects have to do with the details of construction and arrangement of parts as will be hereinafter more fully stated.

My invention is illustrated in the accompanying drawings, wherein:—

Figure 1 is a side elevation of a well drilling rig provided with my invention, the two sections of the walking beam being disconnected;

Figure 2 is a fragmentary top plan of the crank motion for the walking beam;

Figure 3 is a section on the line 3—3 of Figure 1;

Figure 4 is an elevation partly in section of the walking beam structure showing the two sections of the walking beam in operative engagement;

Figure 5 is a top plan view of the walk-

ing beam structure with the two sections 55 in engagement with each other, the guide 12 and the uprights 11 being in section;

Referring to these Figures, 10 designates parallel sill beams and 11 a pair of vertical supporting beams, the sill beams and supporting beams being spaced from each other. 12 designates an upright rigidly attached to the sill beams and formed adjacent its upper end with a vertically extending aperture 13. Mounted upon the sills 10 at one end 65 thereof is a shaft 14 which may be mounted in bearings to oscillate or may be fixed. This shaft forms a support for an oscillatable arm which is formed in two sections 15 and 16, these sections being formed to embrace the shaft 14 and being held together by bolts 17 or any other suitable means for this purpose. The confronting faces of the members 15 and 16 are formed to provide a longitudinally extending slot 18 when the 70 two sections are held together, and provide the bearing 19 for a wrist pin 20, whereby the oscillatable beam is operatively connected to a pitman 21.

The confronting walls of the slot 18 are preferably reduced in thickness to provide tracks with which a slide 22 engages, the slide being formed in its opposite edges with grooves to receive these tracks, and this slide is formed in two sections bolted together by bolts 23 85 so as to embrace the crank 24 of a crank shaft 25 which is suitably connected to a source of power (not shown). The extremities of the slide carry rollers 26 which bear upon the confronting faces of the slot 90 18. Any suitable means may be provided for anti-frictionally supporting the slide 22 within the slot 18, and I do not wish to be limited to the means shown. It will be obvious now that upon a rotation of the crank 95 shaft 25 in the direction of the arrow that the beam formed of the members 15 and 16 will be oscillated upon its pivot 14 and that it will communicate a reciprocation to the pitman 21.

Oscillatably mounted upon a shaft 27 suitably supported in and extending across the space between the uprights 11 is a walking beam. This beam is composed of two sections, one of the sections being designated 105 generally 28. This section 28 of the walking beam is formed of two beams 29 spaced from each other by a spacing member 30

adjacent the free end of the beam and by a spacing member 31 adjacent the pivoted end of the beam, and disposed between these two beams are the pulleys 32 and 33. This beam, composed of the two members 29, extends through the slot 13 in the upright 12 and is guided thereby. The second section of the walking beam is designated generally 34 and is also composed of two beams or members 35 connected at their free ends by transverse members 36, each of these beams 35 being longitudinally slotted, as at 37, the shaft 27 passing through these slots. The pulley 32 is concentric to this shaft, that is concentric to the center of motion of the walking beam as a whole. The free end of the section 34 of the walking beam carries a transverse pin 38, to which the pitman 21 is connected. The free ends of the beams forming the section 28 are inwardly recessed, as at 39, and as these beams 29 forming the member 28 are spaced from each other, it follows that the pin 38 will seat in the recess 39 and that when the parts are so arranged, the pitman 21 will be disposed between the members 29. The section 34 of the walking beam is longitudinally shiftable upon its pivot 27 by a lever 40 which is pivoted, at 41, and which at its upper end is connected, 30 by a link 42 to one of the beams 35. This lever may have any suitable locking device operating over a rack to engage the lever in either of its shifted positions.

Attached to the free end of one of the beams 29 and extending down therefrom is a guard formed of a strip of metal 43 which is attached to the under face of the beam 29 and extends to the tip end of the beam 29, then extends downward and slightly rearward, and then extends rearward and upward and is attached to the under face of the beam 29. A drill cable 44 extends over the crown of the derrick, for instance, (not shown) and is connected, of course, to the usual drill jars and tools, and this cable extends downward from the crown of the derrick beneath the pulley 33, then upward and rearward around the pulley 32, and downward to the usual winding drum (not shown).

The operation of this mechanism is as follows: Assuming that the lever 41 is shifted so as to retract the beam 34 and carry the wrist pin 38 into the seat 39, then it follows that upon a rotation of the crank shaft 25 in the direction of the arrow, that the two sections 28 and 34 the walking beam will be oscillated together to alternately lift and drop the drilling tool in the usual manner. 60 When, however, it is desired to stop the reciprocations of the cable 44 and of the drill tools without, however, stopping the operation of the driving mechanism, then the lever 40 is shifted in a direction to shift the section 34 of the walking beam toward the right

in Figure 4, carrying the wrist pin 38 out of its seat in the recesses 39 (as in Figure 1), and then it follows that the reciprocation of the section 34 of the walking beam will not affect section 28, and that the section 34 70 will oscillate without actuating the section 28 until the section 34 is raised to carry the wrist pin 38 opposite the mouths of the recesses 39, and then if the lever be shifted, the pin 38 will be carried into these recesses 75 and the two sections 28 and 34 of the walking beam will be locked together for unitary oscillation. The guard 43 prevents the section 34 from accidentally moving rearward and thus carrying the pin 38 into engagement in the recesses 39. 80

It will be seen that in effect I have provided a walking beam formed in two sections and with a shiftable clutch whereby one section may be shifted into or out of clutching 85 engagement with the other section.

The particular advantage of the crank motion which I have applied in the operation of the walking beam is that it provides for a relatively slow lifting of the drill cable 90 and a relatively fast drop. This is due to the fact that the crank 24 is nearer to the axis of the beam or element 15 when the cable is being dropped than it is when the cable is being lifted. It will be seen that this mechanism is very simple, that it may be readily retracted, and that by its means the two sections of the walking beam may be readily coupled to or uncoupled from each other, and that by its means a differential movement of the drilling cable is secured. The guard 43, of course, acts to prevent the engagement of the two sections of the walking beam unless the lever 44 has been fully thrown, as unless the lever has been fully 105 thrown, the curved faces of the guard will simply act to shift the section 34 of the walking beam outward, that is away from the section 28. It will be understood that the guard 43 also acts to prevent the outer beam 110 from shifting rearward too far under the inner beam, that is prevent the wrist pin 38 of the beam 34 from being retracted to such position beneath the beam 28 that the wrist pin could not engage in the recess 39. In the 115 drawings, the angular distance between the beam 28 and 34 is exaggerated, but it is to be understood that the wrist pin 38 never drops entirely below the guard 43. The upright 12 acts to prevent lateral movement 120 of the two sections of the walking beam and holds both of said sections from any side motion. It may be stated that this compound walking beam has been found extremely effective in actual service.

I claim:

1. A construction of the character described including a constantly reciprocated pitman, a walking beam with which said pitman is adapted to engage at one end, and

means for shifting the last named end of the pitman into or out of engagement with the end of the walking beam.

2. A construction of the character described including a constantly reciprocated pitman, a walking beam having a notch at one end, and means for shifting the upper end of the pitman into or out of engagement with said notch to thereby operatively connect the pitman with the walking beam or disconnect it therefrom.

3. A construction of the character described including a constantly reciprocated pitman, a walking beam having a notch at one end, means for shifting the upper end of the pitman into or out of engagement with said notch to thereby operatively connect the pitman with the walking beam or disconnect it therefrom including a member pivoted at one end and having operative engagement at its other end with the free end of the pitman, and means for shifting said member longitudinally to carry the pitman into or out of the notch in the walking beam.

25 4. A walking beam of the character described composed of two sections, both of said sections being pivoted upon a common pivot and one of said sections being longitudinally slidable with relation to the other section, the slidable section having means whereby it may be oscillated, the other section being adapted to be connected to an element to be reciprocated, the two sections being formed at one end for interlocking engagement when the shiftable section is shifted in one direction; and means for shifting the said shiftable section into or out of engagement with the other section.

5. A walking beam of the character described formed of two sections, one of said sections being pivotally supported for oscillation and being adapted to be connected to an element to be reciprocated, the other section being slidably mounted for movement toward and from the first named section, the two sections at one end being formed for interlocking engagement when the slidable section is shifted in one direction and for disengagement when the slidable section is shifted in the opposite direction, and manually operable means for sliding said shiftable section into or out of engagement with the other section.

6. A walking beam of the character described formed of two sections, one of said sections being pivoted at one end for oscillation and at its opposite end formed with a longitudinally extending recess, the other section being longitudinally slidable with reference to the first named section and being oscillatably mounted and carrying a wrist pin adapted for insertion into said recess upon the longitudinal movement of the second named section in one direction, a pitman connected to said wrist pin whereby

power may be transmitted to oscillate the slidable section, and manually operable means for shifting the slidable section into or out of engagement with the first named section.

7. A walking beam including a pivoted member having a recess in one end, a pitman having a wrist pin and operatively connected to means whereby the pitman may be reciprocated, and manually operable means for shifting said pitman into or out of engagement with the recessed extremity of the first named section and holding the pitman in such engagement or out of such engagement.

8. A mechanism of the character described comprising a walking beam composed of two sections, one of said sections being pivoted adjacent one end and the other end of the section being formed with a longitudinally extending recess transverse to the arc of movement of the section, the other section being formed of two members spaced from each other to embrace the first named section and having sliding and pivotal movement upon the same center of motion as the first named section, a pitman connected to the wrist pin, said wrist pin, when the shiftable section is shifted in one direction, engaging in said recess to lock the two sections of the walking beam together and disengaging them from the recess upon a movement of the shiftable section in the reverse direction, means for reciprocating the pitman, and manually operable means for shifting the shiftable section in either direction and locking it in shifted position.

9. A structure of the character described including supporting members, a vertically slotted guide element, a walking beam section disposed between the supporting members and extending through the said slot and being adapted to be connected to an element to be reciprocated, the free end of this walking beam element being formed with a longitudinally extending recess, a pivot member passing through the supporting members and through the walking beam section and pivotally supporting it for oscillation, a second walking beam section comprising two members spaced from each other to embrace the first named section and longitudinally slotted at one end, the pivot member of the first named section passing through said slots whereby the second section is longitudinally shiftable with relation to the first named section, a wrist pin extending between the two members of the second named section and adapted, when the second named section is shifted in one direction, to engage in said recess and when it is shifted in the opposite direction to disengage from said recess, a power operated pitman connected to said wrist pin, the members of the second named section operating on each side of the

guide element, and manually operable means for shifting the shiftable section of the walking beam to carry its wrist pin into or out of engagement with the recess in the first named section.

10. A structure of the character described comprising two uprights, a walking beam section composed of two members spaced from but extending parallel to each other and operatively engaged with each other, a pivot pin passing through the uprights and through the two members of the section and pivotally supporting it, pulleys mounted between said members of the walking beam section, the free extremity of the walking beam section being formed with a longitudinally extending recess, a second walking beam section formed of two members disposed on each side of the first named section and spaced from each other, the members of the second named section being formed with longitudinal slots through which the pivot pin of the first section passes, a wrist pin carried by the free ends of the members forming the second section, a pitman connected to said wrist pin, the wrist pin being insertible into said recess or removable therefrom as the second section of the walking beam is shifted longitudinally, means for reciprocating the pitman, a lever, and a link connecting the lever to the second named section of the walking beam whereby the second named section may be shifted.

11. A structure of the character described comprising two uprights, a walking beam section composed of two members spaced from but extending parallel to each other and operatively engaged with each other, a pivot pin passing through the uprights and through the two members of the section and pivotally supporting it, pulleys mounted between said members of the walking beam section, the free extremity of the walking beam section being formed with a longitudinally extending recess, a second walking beam section formed of two members disposed on each side of the first named section and spaced from each other, the members of the second named section being formed with longitudinal slots through which the pivot pin of the first section passes, a wrist pin carried by the free ends of the members forming the second section,

a pitman connected to said wrist pin, the wrist pin being insertible into said recess or removable therefrom as the second section of the walking beam is shifted longitudinally, means for reciprocating the pitman, a lever, a link connecting the lever to the second named section of the walking beam whereby the second named section may be shifted, and a guard attached to the free extremity of one of the members forming the first named section of the walking beam and extending downward and rearward therefrom to engage said wrist pin and prevent accidental shifting of the second named section relative to the first named section.

12. A structure of the character described comprising two uprights, a walking beam section composed of two members spaced from but extending parallel to each other and operatively engaged with each other, a pivot pin passing through the uprights and through the two members of the section and pivotally supporting it, pulleys mounted between said members of the walking beam section, the free extremity of the walking beam section being formed with a longitudinally extending recess, a second walking beam section formed of two members disposed on each side of the first named section and spaced from each other, the members of the second named section being formed with longitudinal slots through which the pivot pin of the first section passes, a wrist pin carried by the free ends of the members forming the second section, a pitman connected to said wrist pin, the wrist pin being insertible into said recess or removable therefrom as the second section of the walking beam is shifted longitudinally, means for reciprocating the pitman, a lever, and a link connecting the lever to the second named section of the walking beam whereby the second named section may be shifted, and a vertical guide extending upward between the members of the second named section and holding them from lateral movement, said guide being vertically slotted to receive the members of the first named section of the walking beam.

In testimony whereof I hereunto affix my signature.

ROBERT W. JAMISON.
